UNITED STATES PATENT OFFICE.

WILLIAM B. SULLIVAN, OF CHICAGO, ILLINOIS, ASSIGNOR TO RICH TOOL COMPANY, OF CHICAGO, ILLINOIS, A CORPORATION OF ILLINOIS.

HARDENED STEEL TOOL.

1,399,414.

Specification of Letters Patent.

Patented Dec. 6, 1921.

Application filed February 24, 1920. Serial No. 360,659.

To all whom it may concern:

Be it known that I, WILLIAM B. SULLIVAN, a citizen of the United States, and resident of Chicago, county of Cook, and State of Illinois, have invented certain new and useful Improvements in Hardened Steel Tools, of which the following is a specification, and which are illustrated in the accompanying drawings, forming a part thereof.

10 The invention relates to steel tools and particularly to those which are hardened by heat treatment and which are of such shape as to present abrupt changes in size between different parts. The object of the invention 15 is to provide a hardened steel tool of improved design whereby there is a more gradual change in the mass of metal employed in different parts of the tool than would otherwise result from abrupt changes 20 in external configuration or size. A feature of the invention also serves to facilitate the dissipation of heat from the head of the tool when used upon hot work.

In the accompanying drawings;

25 Figure 1 is a perspective view showing one form of hardened steel tool embodying the invention;

Fig. 2 is a central longitudinal sectional view of the same;

30 Fig. 3 is an end view of the tool illustrated in Figs. 1 and 2, and

Fig. 4 is a side elevation showing the tool heretofore in common use for the same purpose, partly broken away.

35 The particular tools represented in the drawing are designed for use with so-called air hammers which operate by repeated blows of a piston (not shown) upon the end of the shank, as 10, (Fig. 4) of the tool 40 while the head 11 of the tool is held against the work. In order that such a tool may be effective in service, it should present as little inertia as possible under the impacts of the said piston. It is therefore imperative that 45 the weight of the tool should not be excessive. For this purpose the tool is constructed with its shank 10 of reduced diameter as compared with the size of the head 11.

On the other hand, to prevent ejection of 50 the tool from the air hammer in event of operation of the hammer when the head of the tool is not in contact with the work, the tool must be formed to present a forwardly facing annular shoulder, as 12, of relatively 55 large diameter in rear of the operative part

of the head. Usually there is also a cylindrical surface, as 13, extending forwardly from the said shoulder 12. In practice this cylindrical part of the tool slides within the retainer (not shown) of the air hammer and 60 the shoulder 12 serves to limit the said sliding movement in one direction.

It accordingly follows that the head 11 and shank 10, of the tool, are not only widely different in size but that the expansion from the size of the shank 10 to the size of the head 11 is quite abrupt. There is thus a wide difference in the mass of metal immediately adjacent the two sides of 65 the plane, as 14—14, at which the shank 10 70 joins the head 11.

It is also requisite of tools employed with air hammers, that they should be hardened throughout. This is for the reason that wear is to be resisted at both ends of the tool 75 while hardness between the ends is required to resist distortion under the rapidly repeated blows of the said air hammer piston. Owing to the abrupt change in the mass of the tool at the plane indicated by the said 80 line 14—14 on Fig. 4, the hardening of the tool may result in presence of cooling strains at this place, and in the use of the tool this part is subjected to the greatest strain and may develop fatigue. In any event fracture 85 and complete separation of the head and shank of the tool frequently occur in service and these conditions are believed to be contributing causes.

In carrying out the invention, the head of 90 the tool adjacent the shank is formed to provide a tapering recess preferably without change in the exterior dimensions of the tool, the largest part of the recess being at the plane of union between head and shank. 95 The change in the relative mass of metal between head and shank is thereby made much more gradual than has heretofore been the case in tools of like shape.

As shown in Figs. 1, 2 and 3, the head 16 100 of the tool is recessed in the manner just indicated by being provided with a plurality of slots 15 of varying depth, the said slots being equally spaced about the head 16 adjacent the shank 17. When these slots are 105 provided, the floor 18 of each slot is preferably flush with the exterior surface of the shank 17 at one end and gradually approaches the exterior surface of the head 16 with which it merges intermediate the ends 110

2
of the head, as at 19. The said forwardly facing annular shoulder 12 and the adjacent cylindrical surface 13 are thus interrupted at intervals by the slots 15, but this does not impair their usefulness in coöperation with the corresponding parts of the air hammer (not shown).

On the other hand, when the tool is quenched from a high temperature, for 10 hardening the same, sudden change in the rate of cooling at the union of the head 16 and shank 17 is avoided and cooling strains are less likely to be developed at that place or elsewhere in the tool. In fact, the presence of the slots 15 serves to increase the 15 rate of cooling of the head 16 when the tool is quenched for hardening and these slots likewise facilitate the dissipation of heat from the head when the tool is used upon 20 hot work, as in rivet setting. Furthermore, the provision of the slots 15 also avoids, in a large measure, increased rigidity of the tool in the adjacent part of the head 16 as compared with the shank 17. The strains

to which the tool is subjected in service are 25 therefore less concentrated at the union of the head and shank than in the case of tools of the form illustrated in Fig. 4 and the tendency to fracture at this place is greatly reduced.

30 I claim as my invention:

A hardened steel tool comprising integrally formed cylindrical head and shank arranged in longitudinal alignment but differing substantially in size and expanding abruptly between the shank and head, a part of the head of the tool adjacent the shank being provided with an annular series of longitudinal grooves of gradually diminishing depth leading from the union of the head with the shank and disappearing entirely intermediate the length of the head, the bottoms of the grooves being flush with the exterior of the adjacent part of the shank at one end and with the exterior of the adjacent part 45 of the head at the other end of the grooves.

40 WILLIAM B. SULLIVAN.
